US00D559851S

(12) **United States Design Patent** (10) **Patent No.:** **US D559,851 S**
(45) **Date of Patent:** **** Jan. 15, 2008**

(54) **ARROW KEY**

(75) Inventors: **Wen-Sheng Lee**, Taipei (TW);
Chao-Lung Chang, Miaoli County
(TW)

(73) Assignee: **Darfon Electronics Corp.**, Taoyuan
(TW)

(**) Term: **14 Years**

(21) Appl. No.: **29/276,430**

(22) Filed: **Jan. 25, 2007**

(30) **Foreign Application Priority Data**

Aug. 4, 2006 (TW) 95304368

(51) **LOC (8) Cl.** **14-02**

(52) **U.S. Cl.** **D14/455**

(58) **Field of Classification Search** D14/454,
D14/455, 456, 439, 432, 390, 391, 392, 393,
